Primary Examiner — Derrick Holland*Assistant Examiner* — Jennifer O King(74) *Attorney, Agent, or Firm* — Richard T. Ogawa; Ogawa P.C.(57) **CLAIM**

The ornamental design for a solar tracker frame, as shown and described.

DESCRIPTION

FIG. 1 is a perspective view of a solar tracker frame showing my new design;

FIG. 2 is a perspective view thereof, shown in environmental use;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The broken lines shown represent unclaimed subject matter and form no part of the claimed design.
